MIXING MACHINE

Harry J. Seaman, Milwaukee, Wis.

Application May 26, 1943, Serial No. 488,539

3 Claims. (Cl. 259—6)

1

The present invention relates to mixing machines adapted for preparing road materials and the like.

An object of the invention is to provide an improved machine for effecting a thorough and expeditious mixing and pulverizing of road-building aggregates and for uniformly incorporating therewith a stabilizing material such as a bituminous binder.

Another object is to provide a mixing machine having simple but effective means for permitting yielding of a mixing rotor thereof upon encountering obstructions in the material or excessively heavy loads.

A further object is to provide a mixing machine having simple and durable means for driving a plurality of mixing rotors.

A still further object is to provide a mixing machine which can be inexpensively manufactured, which is reliable in operation, and which will permit ready access to operating parts.

The invention further consists in the several features hereinafter described and claimed.

In the accompanying drawings, illustrating certain embodiments of the invention,

Fig. 1 is a side elevation of one form of mixing machine constructed in accordance with the invention;

Fig. 2 is a longitudinal sectional elevation of the machine;

Fig. 3 is a transverse sectional view, taken generally along the line 3—3 of Fig. 2;

Fig. 4 is a detail top view of a mixing rotor and its mounting;

Fig. 5 is a view similar to Fig. 2, but showing a modified form of mixing machine;

Fig. 6 is a transverse sectional elevation of the machine of Fig. 5, taken generally along the line 6—6 of Fig. 5, and

Fig. 7 is a sectional view taken generally along the line 7—7 of Fig. 5.

Referring to the construction shown in Figs. 1 to 4, 10 designates a frame which includes parallel inclined stringers 11, 12, and 13 at its upper portion and further includes horizontal bottom skids 14 permitting the frame to be detachably carried by a suitable wheeled vehicle such as a trailer 15. At one end of the frame is mounted a power unit 16, preferably of the type including an internal combustion engine, which transmits power through a horizontal drive shaft 17 extending longitudinally of the frame. The shaft 17 is enclosed in a tubular member 18 having a gear housing 19 at the end distant from the power unit, the other end of the tubular member being

2

swingably mounted on a transverse horizontal pivot 20 adjacent to the power unit, so as to permit the tubular member and attached gear housing to be swung in a vertical plane. The end of the shaft 17 within the gear housing carries a bevel pinion 21, Fig. 2, which meshes with a bevel gear 22 on a transverse horizontal shaft 23 journaled in the gear housing. A sprocket wheel 24 is carried on the shaft 23 exterior to the gear housing for driving mechanism hereinafter described. The swingably mounted gear housing is retained at a selected elevation by a bolt 25 engaging a supporting plate 26 on the frame, the plate having a series of openings 27 for selectively receiving the bolt.

A conveyer 28 of the belt or apron type extends between the inclined frame stringers 11 and 12 and comprises a series of overlapping cross slats 29 secured to a pair of side chains 30. The chains 20 pass over sprocket wheels 31 and 32 carried on respective horizontal shafts 33 and 34 which are journaled in self-aligning bearings 35 and 36 secured to the underside of the stringers 11 and 12 near the opposite ends of these stringers. The 25 conveyer has a straight, inclined upper run forming an elevator, the side chains 30 of this portion of the conveyer riding on trackways 37 secured to the frame. The lower conveyer shaft 34 is adjustable to take up wear and slack in the conveyer. The upper conveyer shaft 33 has a sprocket wheel 38, Fig. 3, secured to one end thereof and connected by a chain 39 to a small sprocket wheel 40 on a shaft 41, Fig. 2, the chain drive being enclosed in a housing 42. The shaft 41 is 35 intermediate and parallel to the conveyer shafts 33 and 34 and is journaled in self-aligning bearings 43 secured to the frame stringers 11 and 12. A large sprocket wheel 44, Figs. 1 and 3, is secured to the end of the shaft 41 distant from the sprocket wheel 40.

Extending transversely above the upper run of the conveyer are two power-driven mixing rotors 45 and 46, the axes of rotation of the rotors being approximately horizontal and being spaced 45 longitudinally of the stringers and arranged at opposite sides of the vertical plane of the shaft 41. Each rotor comprises a tubular shaft 47 having detachably secured thereon several rows of resilient hooked tines or teeth 48, the teeth 50 being hooked in the direction of rotation, and the teeth at the underside of the rotors moving in the same direction as the upper run of the conveyer. A spool-shaped bushing 49, Fig. 3, is pressed and welded into an end of the tubular shaft 47 and is rigidly carried on an aligned

shaft 50. The shaft 50 of each rotor is journalled in self-aligning anti-friction bearings 51 secured to the opposite parallel bars 52 of a tiltably mounted rectangular bearing frame or support 53, Figs. 3 and 4. The outer side bar of the bearing frame 53 carries a pivot rod 54 extending transversely of the rotor shaft and parallel to the frame stringers 13, the rod being journalled at opposite ends in spaced pillars 55 upstanding from the stringer 13. The normal horizontal position of the rotor is determined by a post 56, Fig. 3, upstanding from the stringer 12, the post 56 having an adjustable jack screw 57 on which the rectangular bearing frame normally rests.

The two mixing rotors 45 and 46 are enclosed by an elongated inclined hood-forming casing 58 which extends above the upper run of the conveyer and is supported by the frame stringers 11 and 12. At its lower end the casing 58 forms a hopper 59 for the road material to be mixed, the side of the hopper adjacent to the rotor 45 being formed by an inclined flat gate 60 which is slidable in the casing to adjust the thickness of the bed of material moving upwardly along the conveyer. The adjustment of the gate is effected by a rack-and-pinion connection 61, Fig. 2, the pinion shaft having a handwheel 62, Fig. 3, accessible at the side of the casing 58 supported by the stringer 11.

The lower edges of the side walls of the casing 58 have outturned longitudinal flanges 63, Fig. 3, extending above and along the opposite side portions of the upper run of the conveyer. The casing side wall adjacent to the stringer 12 is slotted to receive the rotor shafts 50, the slotted portions being closed by detachable slotted cover plates 64. The other casing side wall is provided with rectangular openings 65 for access to the rotors, these openings being normally closed by removable panels 66 which are adjacent to the free ends of the rotors. A transverse baffle plate 67, Fig. 2, extends between the side walls of the casing 58 at a region about midway between the mixing rotors 45 and 46. Extending transversely in the casing near the upper portion thereof are spray pipes 68, 69, and 70 adapted for pressure spraying a suitable liquid binder, such as bituminous oil, onto the material being mixed. The spray pipe 68 is disposed in the casing chamber having the rotor 45, and the spray pipes 69 and 70 are in the chamber having the rotor 46. Some or all of the spray pipes are provided with shield plates 71. The spray pipes are connected to a supply header 72, extending along one side of the casing 58, each spray pipe having a valve 73, Figs. 1 and 3. The casing 58 has a vertical end wall 74 spaced from the discharge end of the conveyer to permit the downward passage of the material.

The mixed material moving over the upper end of the conveyer drops into a mixing chamber 75, Figs. 2 and 3, constituting an extension of the casing 58, the chamber 75 having a concave bottom wall 76 and an angular cover member 77 forming a top wall 78 and a side wall 79 and presenting a downwardly opening discharge passage 80 between the outer edge of the concave bottom wall and the lower edge of the side wall 79. The cover member 77 is pivoted at 81 for access to the chamber 75. A mixing rotor 82 extends horizontally in the chamber 75 in parallel relation to the other mixing rotors, the axis of the rotor 82 being below the level of the conveyer shaft 33. The rotor 82 is generally similar to rotors 45 and 46 except that it has aligned

shafts 83 at both ends journalled in self-aligning bearings 84 secured to the machine frame. One of the rotor shafts 83 carries a sprocket wheel 85 which is connected by a chain 86 to a similar sprocket wheel 87 on the shaft 50 of the mixing rotor 46.

The shafts 50 of the first and second stage mixing rotors 45 and 46 are each provided with a sprocket wheel 88 arranged close to the vertical plane of the pivot rods 54 for the tiltably mounted rotors and disposed in the vertical plane of the sprocket wheels 24 and 44. An endless driving chain 89, Fig. 1, is trained over the sprocket wheels 24, 44 and 88, thereby driving the conveyer and also the first and second stage mixing rotors. The chain 89 has a reentrant portion extending over the sprocket wheel 44, thus increasing the arc of chain engagement on the sprocket wheel 88 of the second stage mixing rotor 46. The tension of the driving chain 89 is adjusted by raising or lowering the pivotally mounted gear housing 19. The final mixing rotor 82 is driven by the chain 86 from the shaft of the second stage mixing rotor.

In operation, loose road material or aggregate, such as crushed stone, gravel, or sand, or mixtures thereof, is placed in the hopper 59. From the hopper the material passes upwardly along the inclined upper run of the conveyor 28, the depth of the bed of material being regulated by the gate 60. The conveyer is driven at a suitable low rate of speed by the reduction gearing comprising the large sprocket wheel 44 at one end of the shaft 41, and the chain drive at the other end of this shaft. As the material on the conveyer reaches the zone of action of the rotor 45, it is coated with the liquid bituminous binder sprayed onto the material from the pipe 68 and is mixed and pulverized by the rotor, the material being thrown about by the rotor teeth against the walls of the rotor chamber and being in suspension during the application of the binder. In a similar manner, the material is further mixed and bituminated by the second stage rotor 46, and thereafter drops over the upper end of the conveyer into the mixing chamber 75, where it is given a final thorough mixing action by the rotor 82. Practically all of the material passing into the chamber 75 falls into the path of the rotor teeth. The thoroughly mixed bituminated material is gradually discharged through the passage 80 as indicated by the arrow in Fig. 2. The finished material may fall directly onto a road bed or into vehicles for further transport.

The first and second stage mixing rotors are each tiltably mounted and are capable of yielding upwardly when encountering excessive resistance, as indicated by broken lines in Fig. 3, thus avoiding damage to the mechanism by hard lumps or foreign objects in the material or by excessively heavy feeding. At the lower portions of their travel, the outer ends or tips of the teeth of the rotors 45 and 46 are normally spaced a short distance above the upper run of the belt conveyer, and this spacing can be readily adjusted by the jack screws 57, so as to position the rotors during assembly and to compensate for subsequent wear on the rotor teeth.

The modified form of mixing machine shown in Figs. 5 to 7 includes a suitably driven final mixing rotor 182 similar to the rotor 82 of the machine of Figs. 1 to 4 but having its horizontal axis arranged transversely of the axes of the first and second stage rotors. In the modified machine, 75 the frame 110 supports a rotor casing 158 the

front end wall 174 of which extends downward to form the end wall of a mixing chamber 175 for the rotor 182. The side walls of the casing 158 have portions which slope and converge downward to form walls of the chamber 175, as seen in Fig. 6, one of these walls merging into a concave bottom wall 176 of the chamber. The mixing chamber also has an angular cover member 177 similar to the cover member 17 of the machine of Figs. 1 to 4, and forming with an edge of the concave bottom wall a downwardly directed discharge passage 180. The mixing rotor 182 has shaft extensions 183 journalled in bearings 184 on the frame 110, one of the shaft extensions having a sprocket wheel 185.

The final mixing rotor is so located that the stream of material dropping from the conveyer will be more or less centered with respect to the length of the rotor, and a large part of the material will fall into the path of the rotor teeth. In passing from the upper end of the conveyer to the final mixing rotor the material will have a crosswise component of travel which will tend to improve the mixing action.

The side walls of the casing 158 are here shown to be provided with deflectors 190 adjacent to the upper run of the conveyer and in advance of the first and second stage mixing rotors 45 and 46, so as to urge the bed of material on the conveyer away from these side walls and into the path of the mixing teeth on the rotors.

The machine of Figs. 5 to 7 is otherwise similar to that of Figs. 1 to 4 and operates in substantially the same manner.

What I claim as new and desire to secure by Letters Patent is:

1. In a mixing machine, the combination of an endless belt conveyer having an upper run for supporting thereon loose material to be mixed and

for carrying the material therealong, a mixing rotor disposed transversely over said conveyer run for operating on the material, a casing extending over said rotor, means for supporting said rotor from one end thereof and having a pivotal axis extending transversely of the rotor axis to permit upward tilting of said rotor when encountering excessive resistance to rotation, and means for driving said rotor including a sprocket wheel on said rotor adjacent to the vertical plane of the axis of tilt.

2. In a mixing machine, the combination of an endless belt conveyer having an upper run for supporting thereon loose material to be mixed and for carrying the material therealong, a power-driven mixing rotor disposed transversely over said conveyer run for operating on the material, a casing extending over said rotor and having opposite side walls with edge portions adjacent to said run, means for supporting and driving said rotor at one end thereof, the side wall of said casing adjacent to the free end of said rotor having an aperture for access to said rotor, and means for normally closing said aperture.

3. In a mixing machine, the combination of an endless belt conveyer having an upper run for supporting thereon loose material to be mixed and for carrying the material therealong, a power-driven mixing rotor disposed transversely over said conveyer run for operating on the material, a casing extending over said rotor, a support at one end of said rotor having axially spaced bearings for carrying said rotor, means for tiltably mounting said support to permit upward displacement of said rotor when encountering excessive resistance to rotation, and stop means for determining the normal position of said tilttable rotor-carrying support.

HARRY J. SEAMAN.
